UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,030, dated July 3, 1883.

Application filed May 4, 1883. Term of patent 3½ years.

To all whom it may concern:

Be it known that I, PAUL PIGNOT, of Yonkers, in the county of Westchester and State of New York, have invented a new and original 5 Design for Carpets, of which the following is a specification.

The accompanying photograph illustrates my new design for carpets.

This invention relates to a new design for 10 carpets, oil-cloths, and analogous fabrics; and it consists of the new ornamentation of parts hereinafter more fully pointed out.

A scroll-like figure, A, containing a rosette, a, and supporting a pedestal-like figure, b, is 15 in part covered by a large bouquet, B, of flowers and leaves. Above this bouquet B is an-

other scroll-like figure, C, adjoining and connecting with a pentagonal figure, D, and with a pendant, E, which figure C is also in part covered by a bouquet, F, of flowers, as shown. 20 The effect of the bouquet B is made striking from the fact that behind the more prominent leaves are partly seen fainter leaves, which have for their effect to raise the said bouquet more clearly from the background. 25

I claim—

The design for carpets, consisting of the figures A B C D E F a b, substantially as shown.

PAUL PIGNOT.
